UNITED STATES PATENT OFFICE

115,991

DESIGN FOR A TEXTILE FABRIC

Curt Erwin Forstmann, Montclair, N. J.

Application November 9, 1937, Serial No. 72,730

Term of patent 3½ years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design unit consists of a central narrow stripe in the form of a ridge with roundish nubs at substantially regular intervals, and a wide stripe on each side of the narrow stripe, each wide stripe comprising a plurality of parallel ridges having nubs in inclined regularly spaced groups arranged herring-bone fashion with respect to the narrow stripe.

I claim:

The ornamental design for a textile fabric as described and as shown.

CURT E. FORSTMANN.
